UNITED STATES PATENT OFFICE

ERNEST DAVIS, OF SYRACUSE, NEW YORK, ASSIGNOR TO THE PROSPERITY COMPANY INC., OF SYRACUSE, NEW YORK, A CORPORATION OF NEW YORK

PRESSING-MACHINE ELEMENT FOR PRESSING MACHINES

Application filed April 5, 1928. Serial No. 267,553.

This invention relates to pressing machines as garment and laundry machines, and particularly to machines which project steam from one of the pressing elements through the pressing face and into or on to the article being pressed, and the invention has for its object a particularly simple and efficient means for separating the water of condensation from the steam and reconverting it into steam so that no water of condensation is projected on to the garment.

The invention consists in the novel features and in the combinations and constructions hereinafter set forth and claimed.

In describing this invention, reference is had to the accompanying drawings in which like characters designate corresponding parts in all the views.

Figure 1 is a longitudinal sectional view of a pressing machine element as a press head embodying my invention.

Figure 2 is a transverse vertical sectional view taken centrally of Figure 1.

Figure 3 is a fragmentary front elevation 25 of a pressing machine element embodying my invention.

1 designates a pressing machine element or platen formed hollow to provide a chamber 2 for receiving a heating medium as 30 steam.

3 is a second internal chamber within the chamber 2 and having perforations 4 opening through the ironing face of the element. The chamber 3 is in the form of a channel 35 extending lengthwise of the head along the median line thereof. The side of the channel opens through the pressing face which is closed by a plate 5 in which the perforations are formed. The chamber 3 is disconnected 40 from or non-communicating with the heating chamber.

6 is a water separator and converter located in the chamber 3 and extending lengthwise thereof, this being in the form of a 45 flattened tube or somewhat kidney shaped tube in cross section, which tube is spaced apart from all of the walls of the chamber 3. The separator and the converter 6 has an inlet 7 opening into the chamber 2 to receive steam therefrom. It is also provided

with upwardly directed outlet openings 8 on sides other than its bottom, these openings 8 being here shown as located in the top wall thereof.

The inlet passage 7 is formed in a bracket 55 9 by means of which the converter and separator 6 is suspended or supported in the chamber 3.

In the illustrated embodiment of my invention, the passage 7 opens into a portion 10 of 60 the chamber 2, which portion 10 extends over the top of the chamber 3.

11 is a valve normally closing the passage 7, this valve having a stem 12 extending through a suitable mounting 13 on the upper 65 side of the element 1 and through a packing 14 in said mounting, the stem 12 being pivoted at 15 to an operating lever 16. The operating lever 16 is pivoted at 17 between its ends and the arm to which the stem is pivoted 70 is connected to a returning spring 18.

Upon depression of the end of the lever provided with a handle 19, the other end of the lever will be lifted against the action of the spring 18 and the valve 11 opened permitting steam to pass through the passage 7 from the chamber 2 to the converter and separator 6.

The head 1 coacts with a suitable buck B mounted in any suitable manner on the frame F of the machine and on which the garment or other article to be pressed is arranged before the head is brought down on to the buck, and the head is carried by a suitable double or yoke lever 22 which is actuated in any well 80 known manner.

In use, the water of condensation is trapped in the converter and the steam passes out from the perforations 8 into the chamber 3 and thence through the perforations 5 to 90 the garment on the buck B. The water trapped in the separator is reconverted into steam by the heat of the steam within the chamber 3.

What I claim is:

1. A pressing machine element formed with a heated bottom chamber having perforations opening through the pressing face of said element, a closed separator and converter conduit located within the chamber and spaced 100

- from the walls thereof, said conduit having steam outlets in the top side thereof and its bottom side imperforate the perforations of said bottom chamber opening into said chamber below said conduit, whereby the steam passing from the outlet into the chamber passes directly through said perforations, and means for supplying and controlling the flow of steam to said conduit.
- 10 2. A pressing machine element formed with a heated bottom chamber having perforations opening through the pressing face of said element, a closed separator and converter conduit oblong in general form in cross section located within the chamber and spaced from the walls thereof, and having the end portions of its oblong formation lower than its central portion, said conduit having steam outlets in the top side thereof, and its bottom side being imperforate, and means for supplying and controlling the flow of steam to said conduit.

In testimony whereof, I have hereunto signed my name, at Syracuse, in the county of Onondaga, and State of New York, this 31st day of March, 1928.

ERNEST DAVIS.
